FOUNDRY SAND RECLAIMING SYSTEM
AND METHOD

Alfred C. Christensen and James J. Dvorak, Chicago, Ill., assignors to Herbert S. Simpson, Evanston, Ill.

Application December 21, 1942, Serial No. 469,662

10 Claims. (Cl. 22—89)

1

This invention relates to a method of and apparatus for more efficiently reclaiming spent and inert used materials by subjecting batches thereof to dry and wet independently timed treatments during a course of travel through a continuously descending gravity feed line.

This invention is a continuation-in-part of our pending application for patent for a "Foundry sand reclaiming system and method," filed February 7, 1942, U. S. Serial No. 429,916.

The present invention, more specifically, relates to an improved and efficient combination dry and wet reclamation system for used materials, such as spent foundry sand and the like, said system including independently timed treatments administered in sequence to measured batches of the material as the batches are simultaneously advanced through a continuously descending gravity feed line, whereby the material not only has the foreign bond substances removed but also has a good percentage of the carbonaceous coating eliminated from the grains thereby producing a resultant reclaimed graded material of substantially its original color.

It is an object of this invention to provide an improved method of and apparatus for reclaiming spent or inert used materials by subjecting the materials to dry and wet treatments to produce a clean, graded and bleached resultant material.

It is also an object of this invention to provide an improved method of and apparatus for reclaiming spent foundry sand and the like, which method is economical, clean and effective.

It is a further object of this invention to provide a gravity feed apparatus for reconditioning previously bonded used granular materials such as used for the making of foundry castings and the like, in order to remove scale, dust and other foreign matter to produce a resultant material which is dried, bleached and graded and is suitable for repeated use.

Another object of this invention is the provision of an apparatus for cleaning and separating material particles of various sizes, which apparatus is arranged to effect a continuously descending gravity feed course and which apparatus is relatively compact and efficient as to floor space.

It is furthermore an object of this invention to provide a method of and an apparatus for cleaning and sorting granular materials to restore the materials for re-use by subjecting the materials to a dry cleaning treatment and subsequently converting the material into a paste-

2

like substance and then, hydraulically treating the paste-like material and eventually drying the resultant graded material as it completes a cycle of treatment.

5 Another object of the invention is the provision of a continuous batch treating system for the reclaiming of foundry sand and the like, said system embodying combination dry and wet treatment adapted to reclaim a high percentage of the sand at a cost materially less than the cost of providing new sand.

A further object of the invention is to provide an improved combination dry and wet treatments for the reclaiming of foundry sand and the like, by means of a gravity feed system for the continuous batch treatment of the sand in timed sequences including hydraulic steps arranged for re-using the water to effect a reduction in the cost of operations of the system.

It is an important object of this invention to provide an improved method of and apparatus for reconditioning spent or inert granular materials by compactly arranging different treatment units of the system to effect a continuously descending gravity feed course for the material through the system by having the various treatment units arranged with independent timing controls connected in a timing system whereby the treated material is separated in batches, with said batches being conducted through continuous cycles in stepped sequences through the apparatus to effect a clean, bleached and graded restoration of the material for re-use.

Another important object of the invention is the provision of an improved and effective method of and apparatus for the reconditioning of spent granular material by a gravity feed of the material through a cycle of operations and treatments in which the material is advanced in predetermined quantities and subjected to a dry cleaning including the removal of fines therefrom after which the material is converted by means of moisture into a paste-like substance which is subsequently subject to desilting and elutriating steps to be wet cleaned and graded and then delivered to a centrifuging treatment to be dried to produce a reclaimed material which is not only cleaned and graded but which is substantially restored to its original color.

50 Other and further important objects of this invention will be apparent from the disclosures in the specification and the accompanying drawings.

In the drawings:

Figure 1 is a fragmentary front elevational

view, in schematic form, of a foundry sand reclaiming system and a time control (embodying the principles of this invention) connected with various elements of the system for automatically timing the operation of the cycle of operations and the various steps thereof.

Figure 2 is a wiring diagram of the electrical control of the cycle of operations of the system and including parts of the various elements in the cycle which are governed by the timers.

Figure 3 is an enlarged sectional view of the upper third of the system including the first three steps of the cycle and the circuits therefor including the total cycle timer and the water control timer for the wet scrubber unit.

Figure 4 is an enlarged fragmentary sectional view of the intermediate portion of the apparatus including the wet scrubber and the desilting unit with their respective timers and the wiring connections.

Figure 5 is an enlarged fragmentary sectional view of the lower section of the apparatus including the elutriating and centrifuging units together with their respective timers and the wiring connections therefor.

As shown in the drawings:

It is believed that the novel method or process, of this invention, may be readily understood from the following description of a machine or apparatus for practicing the same.

The improved combined dry and wet method or process for the reclaiming of spent or inert granular materials such as foundry sand and the like, is adapted to be accomplished more specifically by means of a machine or apparatus to which the materials which have previously been crushed and demetalized are delivered. The inert material such as spent foundry sand, which is to be treated and reclaimed is delivered in measured batches to a series of consecutively arranged treating units in independently timed sequences through consecutively continuous cycles for subjecting the batches of sand, after being measured, to dry scrubbing and dust suctioning, semi-wet scrubbing and mulling, desilting, elutriating and finally to a centrifuging treatment to finally discharge a reclaimed, cleaned, bleached and graded sand ready for re-use.

The spent or inert material, such as used foundry sand, after being crushed and having the metal particles removed therefrom, is delivered into an elevated supply bin or hopper 1 which is supported on an upper level of a structural framework, which has been omitted in the drawings and which may be of any desired construction for supporting the various units comprising the machine or apparatus of this invention. The supporting framework is supported upon a floor or foundation 2 which may be constructed of concrete or other suitable material and in which a pit or chamber 3 is provided.

The supply bin or hopper 1 is the uppermost of a plurality of treating units, which are arranged in a continuously descending sequence to provide a continuous gravity feed line for the material through the succeeding cycles of operation through which the material in measured batches is conducted.

The supply bin or hopper 1 has the lower portion thereof tapered to provide a restricted mouth or outlet neck 4. The material, which is to be weighed out in predetermined quantities or in batches, is carried in the supply bin 1 and is prevented from dropping out of the discharge neck 4 by means of a pair of curved or arcuate doors

5. Each of the doors 5 is provided with end arms 6 which are pivotally supported on pins or stub shafts 7. Each of the door arms 6, beyond the pivot point thereof, is provided with an integral gear segment 8. The gear segments 8 of the bin doors 5 intermesh so that when one of the doors 5 is opened or closed the other door will be simultaneously operated.

One of the bin doors 5 is provided with an arm 9 (Figure 3) to which the lower end of a piston rod or stem 10 is pivotally connected. The piston rod 10 forms part of an air control mechanism comprising an air cylinder 11 which is secured on the exterior of the storage bin 1 by suitable supporting means. Engaged on the inner end of the piston rod 10 and slidably disposed within the air cylinder 11 is a piston head which is adapted to be slidably moved within the air cylinder 11 by means of air pressure adapted to be admitted into the air cylinder alternately below the piston head and above the same respectively by a lower air tube 12 and an upper air tube 13. The lower air tube 12 is connected to one arm of a three-way coupling 14. Connected to the middle arm of the three-way coupling 14 is one end of an air pipe or tube 15. The other end of the air tube 15 is connected to a solenoid operated air valve unit 16. Also connected with the solenoid operated air valve unit 16 is a second air pipe or tube 17, which as shown in Figure 3 is connected to the middle arm of a pipe coupling 18 to another arm of which the upper air tube 13 is connected. Connected to the solenoid operated air valve unit 16 is an air supply pipe or tube 19 which is connected with any suitable source of compressed air.

For the purpose of controlling the operation of the airvalve unit 16, said unit is connected by means of wires 20 and 21 to a selected standard type of time switch unit 22, the internal wiring mechanisms of which are illustrated in the wiring diagrams shown in Figures 2 and 3. The feed control time switch unit 22 is mounted in a control board or casing 23 mounted on the machine framework in any suitable or accessible position or at a remote station from which it is desired to control the operation of the machine. The feed control time switch unit 22 is provided with an outer minute time set dial 24 which is adapted to be set when a lock nut or knob 25 is released. The time switch unit 22 is also provided with an inner dial 26 which is divided into sixty subdivisions for second timing. Both the dials 24 and 26 are adapted to be set with respect to an index mark 27 positioned on the front face of the casing of the time switch unit 22 after the dials have been set the lock nut or knob 25 is tightened to insure operation of the time switch.

For the purpose of measuring predetermined quantities or batches of the material to be reconditioned a batch measuring unit is mounted on the machine framework directly below the outlet neck 4 of the supply bin 1 to receive material therefrom when the bin control doors 5 are opened. The measuring unit comprises a material measuring hopper 28, the open top of which is beneath the discharge neck 4 of the bin 1. The measuring hopper 28 has a tapered body portion which terminates in a discharge neck 29 the outlet of which is controlled by a pair of doors 30 which are of curved or arcuate shape having supporting arms 31 integrally formed on the ends thereof. The door arms 31 are pivotally supported on supporting pins or stub shafts 32 carried on opposite walls of the hopper neck

29. Each of the door arms 31 has a gear segment 33 formed on the upper end thereof. The gear segments 33 of each pair of arms 31 mesh with one another, so that when one of the doors 30 is actuated the opposite door will be operated.

Secured on one of the hopper control doors 30 is a door operating arm 34 to the outer end of which the outer end of a piston rod or stem 35 is pivotally connected. The piston rod 35 forms a part of an air controlled mechanism comprising an air cylinder 36 which is secured on the exterior of the measuring hopper 28. Engaged on the inner end of the piston rod 35 within the air cylinder 36 is a piston head which is adapted to be slidably moved within the air cylinder 36 by means of air pressure admitted into the cylinder below the piston head through a lower air tube 37 and above the piston head by means of an upper air tube 38. The lower air tube 37 is connected to the third end of a T-coupling 16, while the upper air tube 38 is connected to the third end of the T-coupling 14.

The two air controlled door operating mechanisms for the bin doors 5 and the hopper doors 30 are thus both connected to the same solenoid operated air valve unit 16 and to the same feed control time switch unit 22 which is adapted to be set to cause automatic operation, at timed intervals, of the solenoid operated air valve unit 16 to cause opening of the material discharge bin doors 5 and simultaneous closing of the hopper doors 30 when a charge of material to be delivered into the hopper 28, or closing of the doors 5 when the doors 30 are timed to be opened to discharge a measured charge of material from the hopper 28 into a material dry scrubbing and dust removing unit which performs the third step in the sequence of operations undergone by the material as it is advanced through a cycle of treatments to become reconditioned for re-use.

The dry scrubbing unit is supported on the machine framework at a level lower than that of the batch measuring unit to form an arrangement for continuing the gravity feed from the bin 1, then to the hopper 28, and next to the dry scrubbing unit.

As clearly shown in Figures 1 and 3 the dry scrubbing unit comprises an upper scrubber casing section 39 having a material receiving mouth 40. The dry scrubber top section 39 is secured on the upper end of a main dry scrubber casing 41 and has connected to one side thereof one end of a fines and dust discharge pipe 42. The lower end of the dust discharge pipe 42 is connected to a suction or exhaust fan housing 43 which is supported on a dust collector 44 mounted on the machine framework. A suction or exhaust fan within the housing 43 is connected to be operated by a driving motor 45. Attached to the upper end of the exhaust fan housing 43 is the lower end of an air outlet flue or pipe 46 through which air is permitted to escape to the atmosphere as fines and dust are delivered into the collector 44.

The dry scrubber casing 41 contains a motor driven rotor 47 formed with mixing paddles and scrapers 48 for imparting a violent mixing and paddling action to the material delivered by gravity into the dry scrubber casing 41 when the hopper doors 30 are opened and a pair of pivotally mounted dry scrubber casing discharge doors 49 are closed.

The closure doors 49 of the dry scrubber casing 41 have door operating arms 50 connected thereto. The outer ends of the arms 50 are pivotally

connected to the outer end of a pair of piston rods or stems 51 which project from a pair of air cylinders 52 which are supported adjacent the opposite sides of the dry scrubber casing 41.

5 Each of the air cylinders 52 has a piston head therein engaged on the inner end of the piston rods 51. The two cylinders 52 have their lower ends connected by a lower connecting air tube 53, while the upper ends of the cylinders 52 are 10 connected by an upper air tube 54. The two piston mechanisms of the air cylinders 52 operate simultaneously to cause either simultaneous opening or closing of the dry scrubber doors 49.

15 Connected to the lower end of one of the dry scrubber cylinders 52 is one end of an air pressure pipe or tube 55 while one end of a second air pressure pipe or tube 56 is connected to the upper end of the same cylinder 52. The two air control tubes 55 and 56 are connected to a dry scrubber solenoid operated air valve unit 57 having an air pressure supply pipe or tube 58 connected thereto.

The air pressure supply to the air valve unit 57 is controlled by a solenoid within the unit 57 by means of two circuit wires 59 and 60 which are connected to the solenoid terminals to connect the control solenoid with a dry scrubber electric time switch unit 61 which is mounted on the control board 23 and is identical to the time switch unit 22.

30 The fourth step in the cycle of treatments of a batch of the material to be reconditioned, is performed by means of a combination dry and wet mixing, scouring and mulling unit which may be termed the wet scrubber unit. It is mounted upon the machine framework, directly beneath the discharge doors 49 of the dry scrubber unit to form another step in the gravity feed line course for the travel of the material through the machine. The wet scrubber unit comprises a material receiving hopper or chute 62, the lower discharge end of which projects into an upper casing section 63 which is mounted on the upper end of a mixing and mulling pan or casing 64

35 having a material discharge opening in the bottom of one side thereof adapted to be closed by means of a door 65. Axially disposed within the pan or casing 64 is a driving shaft set to be rotated by means of a motor 66. The driving shaft has 40 secured on the upper end thereof, within the casing 64, a head 67 on which mixing and mulling wheels or mullers 68 are rotatably supported. Also carried by the rotatable head 67 are plows or scrapers 69 which are positioned to scrape the 45 bottom and walls of the casing 64 and plow and deliver the material being treated into the path of travel of the rotating wheels or mullers 68.

In order to further dry clean the material in the casing 64 and convert the dry cleaning treatment into a semi-wet treatment to form a resultant paste of the treated material, the wet scrubber unit is provided with a water receiving funnel 70 having one or more water distributing pipes 71 projecting downwardly from the bottom 50 or lower portion thereof for distributing the required amount of water or other liquid into the mixture contained within the casing 64. Projecting into the water receiving funnel 70 is the discharge end of a water feed pipe 72 which connects 55 up with a water control solenoid operated water valve unit 73. Also connected to the water valve unit 73 is a water pipe 74 having a shut-off valve 75 connected therein. Shunted around the shut-off valve 75 is a by-pass pipe 76 (Figure 1) in

60 which a water pressure regulating valve unit 77

is connected; to assure a constant water pressure in the water supply line leading to the solenoid valve unit 73.

For the purpose of controlling the timing operation of the water valve unit 73 the solenoid thereof has connected to the terminal thereof two circuit wires 78 and 79 which lead to a water controlled electric time switch unit 80 which is mounted on the control board 3 and is identical to the time switch unit 22.

As illustrated, in Figure 1, the water pipe 74 is also connected to a desilter water supply pipe 81 which, in turn, connects up with a main water supply pipe 82 having a control or shut-off valve 83 connected therein.

A batch of material which has just been dry scrubbed and from which the fines or dust has been removed is dropped into the receiving hopper or chute 62 of the wet scrubber and is delivered into the casing 64, when the muller casing discharge door 65 is closed and when the dry scrubber discharge doors 49 are opened. The advanced batch of material delivered through the gravity feed line to the mulling casing 64 is first further dry cleaned and then has a predetermined quantity of water discharged thereon, to be mixed therewith, to produce a paste-like substance which is subjected to a thorough mixing and mulling actions for a predetermined length of time determined by the opening of the muller casing discharge door 65.

For the purpose of controlling the operation of the door 65 at timed intervals, the door is provided with an operating or actuating arm 84 to which the outer end of a piston rod or stem 85 is pivotally connected. The piston rod 85 projects into an air cylinder 86 and has a piston head secured on the inner end of the rod 85 to be reciprocated by air pressure. Connected to the lower end of the air cylinder 86 is one end of an air pipe 87. Also connected to the air cylinder 86, at the upper end thereof, is another air pipe 88. Both the air pipes 87 and 88 are connected to a wet scrubber solenoid operated air valve unit 89 having an air supply pipe 90 connected to the air valve within the valve unit. Connected to two terminals of the solenoid within the wet scrubber valve unit are two circuit wires 91 and 92 which are also connected to two terminals of a wet scrubber control electric time switch unit 93 which is mounted on the control board 23 and is identical to the time switch unit 22.

After the wet paste-like material has been treated to wet scrub the particles thereof within the wet scrubber casing 64, the casing door 65 is automatically opened and the paste-like contents is discharged through a chute 94 into a desilting unit which is mounted on the machine framework at a level below the level of the wet scrubber unit so that the feed of material from the wet scrubber unit to the desilting unit may be accomplished by the action of gravity to complete another step in the gravity feed line course of the material through the machine. The desiliter unit comprises a conical container or tank 95 into which the lower discharge end of the feed chute 94 projects. The upper end of the desiliter tank 95 is open and projects part way into a circular or circumferential launder 96 which is provided for the purpose of receiving and discharging the resultant organic matter and silt which is separated from the bath being treated by the desilting operations. Leading downwardly from the desiliter launder 96 is a discharge pipe 97 which projects downwardly through the floor 2 and the

pit 3 and connects up with a sewer unit 98. The lower tapered end of the desiliter casing or tank 95 terminates in a discharge valve casing 99 having a valve seat 100 formed therein with which a discharge control valve 101 co-acts. The discharge control valve 101 is connected to the lower end of a valve stem 102 which projects upwardly through a rotatable hollow shaft 103 and upwardly out of the desiliter casing or tank 95 with the upper end of the valve stem or piston rod 102 projecting into an air cylinder 104 to be operated by a piston head within said cylinder when the same is operated by air pressure to control opening and closing of the desiliter discharge valve 101.

Connected to the lower end of the air controlled cylinder 104 is an air pipe 105. A second air pipe 106 is connected to the upper end of the cylinder 104. Both the air cylinder pipes 105 and 106 are connected with a desiliter solenoid operated air valve unit 107 to which an air pressure supply pipe 108 is also connected to supply air pressure to the pipes 105 and 106 through a valve within the unit 107. The control valve within the unit 107 is adapted to be operated by means of an electric solenoid to the terminals of which two circuit wires 109 and 110 are connected. The two circuit wires 109 and 110 are connected with a desiliter control electric time switch unit 111 which is mounted on the control board 23 and is identical to the time switch 22.

For the purpose of accomplishing a desilting treatment of the paste-like material, which is discharged from the wet scrubber into the desiliter, a water agitating and circulating turbine type wheel 112 is horizontally positioned within the desiliter casing 95 and is secured to the lower end of the hollow rotatable shaft 103 to be rotated thereby. The desiliter unit is provided with an operating motor 113 for causing rotation of the shaft 103 and the water agitating wheel 112. The motor 113 is provided with circuit wires 114 and 115 which connect up to a source of electrical energy. A control switch 116 is connected in the circuit wire 114 for the purpose of controlling the operation of the motor 113.

For the purpose of admitting water into the desiliter casing or tank 95 the desiliter is provided with a circular water pipe 117 to which the water supply pipe 81 is connected. Branching from the circular water pipe 117 are a plurality of auxiliary feed pipes 118 which project into the lower end of the desiliter casing or tank 95 to project water under pressure into the tank. Water admitted into the desiliter tank 95 through the auxiliary pipes 118 is brought into contact with the motor driven turbine type wheel 112 to cause the water to be thoroughly agitated and circulated in the lower portion of the desiliter casing so that the paste-like material which has been deposited into the casing 95 is thoroughly broken up by the action of the water permitting the scrubbed and washed sand grains or granular particles to settle in the bottom of the casing and in the valve casing 99, while the silt and organic matter is carried upwardly by the water in the desiliter casing or tank 95 and overflows into the launder 96 from which it is discharged through the discharge pipe 97 into the sewer 98. Connected to the lower end of the valve casing 99 and below the control valve 101 of the desiliter, is a conical shaped discharge funnel or cup 119 having the upper end of a discharge pipe 120 connected thereto.

After the desilting treatment of the paste-like

material the cleaned batch of material is now ready to be advanced another step in the cycle of operations into an elutriating unit for further washing and grading the material. At the end of a desilting treatment the time switch unit 111 operates to cause opening of the desiliter valve 101 thereby permitting the scoured and cleaned material from the desiliter to be discharged into the funnel 119 and through the discharge pipe 120 into an elutriating unit for further treatment.

The elutriating unit is mounted on the machine framework at a level below the level of the desilting unit to form an arrangement whereby the material is continued to be fed downwardly by gravity. The elutriating unit comprises a tapered or conical shaped casing or tank 121 the upper end of which is open and into which the discharge end of the material feed pipe 120 projects in order to discharge a measured batch or quantity of the material being treated into the elutriating grading casing 121. The upper open end of the elutriating casing 121 projects part way into a circumferential or circular launder 122. Connected to the launder 122 is the upper end of a water discharge pipe 123 which projects downwardly and enters into the upper portion of a water collecting reservoir 124 which is mounted in the pit 3. The water reservoir 124 is connected to the sewer 98 by means of a discharge pipe 125 having a shut-off or control valve 126 connected therein to permit draining of the tank 124 when necessary to permit removal of any sediment or the like which might accumulate in the reservoir 124. Also connected to the reservoir or tank 124 is an overflow pipe 127 which is connected with the discharge pipe 97 leading into the sewer 98.

The lower end of the elutriating casing or tank 121 is provided with a valve seat at 128 surrounding a valve opening which is adapted to be closed by an elutriator control valve 129 for controlling the discharge of cleaned graded material from the elutriator.

Surrounding the discharge mouth or valve end of the elutriator casing 121 is a circular or ring shaped water supply pipe 130 having a plurality of auxiliary water supply pipes 131 connected thereto and projecting into the elutriator casing 121. Connected to the ring shaped water supply pipe 130 is the upper end of a water flow gauge 132 for gauging or regulating the pressure of the flow of water to the elutriator. Connected to the lower end of the flow gauge 132 is a water supply pipe 133 which connects up with the main water supply pipe 82 and has a shut-off or control valve 134 connected therein.

Mounted on the floor 2 above the pit 3 is a water pump 135, having connected thereto one end of a water pipe 136 having the intake end thereon projecting downwardly into the water reservoir 124 so that used water from the launder 122 flowing downwardly through the discharge pipe 123 and used water from a centrifuging unit, hereinafter described, is returned into the reservoir 124. The supply of fresh water from the main supply pipe 82 may be shut off by means of the control valve 83 (Figure 1) so that the previously used water stored in the reservoir 124 may be re-used by operation of the pump 135 which pumps the water from the reservoir up through a pipe 136 which connects the pump 135 with the pipe 133 so that the previously used water may be re-used in the desiliter and in the elutriator thereby providing an arrange-

ment for reducing the water consumption and the cost of operation of the entire system.

The water under pressure entering the elutriator casing or tank 121 through the auxiliary pipes 131 is directed upwardly and is adapted to be thoroughly agitated by means of a turbine type of water wheel 137 which is horizontally disposed in the elutriator casing 121. The wheel 137 is supported on a rotatable hollow shaft 138 which extends upwardly out of the casing 121 and is connected to be operated by means of an elutriator operating motor 139 having circuit wires 140 and 141 connected thereto and to a suitable source of electrical energy. Mounted in the circuit wire 141 is a motor control switch 142 (Figure 5) to provide an arrangement whereby the elutriator motor may have a private control circuit, or the circuit wires for the motor may be connected with the main power line of the system, as preferred. When the control switch 142 of the motor 139 is closed the elutriator agitating wheel 137 is rotated so that the water within the casing 121 is thoroughly agitated as is also the material discharged into the elutriator from the desiliter discharge pipe 120. The elutriator acts as a means for agitating the substantially cleaned sand grains or material particles so that the lighter particles are carried upwardly by the water stream while the heavier grains are permitted to settle toward the bottom of the elutriator casing 121. As the lighter grains and any remaining particles of the material are conveyed upwardly they flow over the top edge of the elutriator casing 121 into the launder 122 and then downwardly through the discharge pipe 123 into the reservoir 124 so that only material cleaned grains of a graded size remain in the elutriator. The grading of the cleaned material in the elutriator casing 121 may be regulated by the water gauge 132 to determine the pressure of the water entering the elutriator casing through the pipes 130 and 131. By the time the material being treated has completed the elutriating treatment, it is thoroughly scrubbed and washed and graded.

The various treatments accorded the material passing through the cycle of operations act to remove not only the foreign bond materials from the material grains but also acts to remove a large percentage of any of the carbonaceous coating from the grains, which is a highly desirable factor in the reclaiming of spent foundry sand on which an oil bond has been used.

For the purpose of controlling the discharge of the cleaned and graded material from the elutriator casing 121 the elutriator control valve 129 is adapted to be operated by a piston rod or valve stem 143 which projects upwardly through the hollow shaft 138 and extends into an air cylinder 144 which contains a piston head secured on the upper end of the piston rod 143.

Connected to the lower end of the air cylinder 144 is one end of an air pressure pipe or tube 145. A second air pressure pipe or tube 146 is connected to the upper portion of the cylinder 144. The two air control pipes or tubes 145 and 146 are connected to an elutriator solenoid operated air valve unit 147 having an air pressure supply pipe or tube 148 connected thereto. The air pressure control valve in the unit 147 is controlled by a solenoid within said unit. Connected to the terminals of the solenoid are two circuit wires 149 and 150 which are connected with an elutriator electric time switch unit 151 which is mounted on the control board 23 and is identical to the

11

time switch unit 22. The elutriator casing 121 has the valve 129 thereof controlled by the timer switch 151 and said valve 129 is not opened to permit discharge of the material therefrom into a centrifuging unit until said centrifuging unit has first been emptied. Connected to the lower discharge end of the elutriator casing 121 is a cone shaped discharge funnel 152 having a discharge pipe 153 connected to the lower end thereof and arranged with the discharge end thereof positioned to discharge a measured cleaned and graded batch of reclaimed material into a centrifuging unit which is adapted to perform the last step in the cycle of treatments to which the batches of material are subjected in their gravitational descent through the machine.

The centrifuging unit is provided to receive the graded, washed and scoured material and to subject the same to a dehydrating treatment to extract the water therefrom to render the cleaned reclaimed material substantially dry and restored to its normal color ready to be discharged for re-use.

The centrifuging unit comprises a casing or tank 154 which is supported on the floor 2 and has an opening 155 in the bottom thereof surrounded by an upwardly projecting flange 156 which forms an annular water-collecting trough in the bottom of the centrifuging tank 154, from which the water is adapted to be drained through a pipe 157. The discharge end of the pipe 157 projects downwardly into the water collecting reservoir 124 to permit the water from the centrifuge to be re-used in the system. As clearly illustrated in Figure 5, the centrifuging tank 154 is positioned so that the opening 155 thereof registers with an opening formed by a collar or ring 158 in the floor 2 above the pit 3. Attached to the bottom of the collar 158 is a material discharge funnel or chute 159 the lower end or discharge mouth of which is positioned above an endless conveyor 160 which is positioned in the pit 3 and which leads outwardly therefrom to deliver the reclaimed or reconditioned material for re-use.

A centrifuge framework 161 is supported on the floor 2 and extends above the tank 154 and has supported on the upper end thereof a downwardly projecting shaft 162. The lower end of the centrifuge shaft 162 is suspended in the tank 154 and has secured on the lower end thereof a conical shaped discharge mouth or funnel 163 which projects through the opening in the bottom of the tank 154 and into the collar 158 for delivery of material to the discharge chute 159. The discharge mouth 163 is supported on the shaft 162 by a plurality of radially directed fins or blades connected to a collar secured on the lower end of the shaft. Secured on the shaft 162 above the discharge mouth 163 is a material receiving disk 164 upon which material from the elutriator is discharged from the pipe 153, so that the cleaned graded material striking the disk 164, while the same is being rotated, rebounds and is discharged centrifugally outwardly into a mesh basket 165 which is secured on the upper flanged end of the mouth 163 and is provided with a top 166 having a central opening through which the shaft 162 and the discharge end of the pipe 153 projects. The material discharged by centrifugal force from the baffle disk 164 when the same is rotated, is discharged outwardly against the walls of the mesh basket 165 thereby permitting the material to be dehydrated allowing the discharged water to pass outwardly through the mesh openings in the mesh basket 165 and drop into the

12

discharge trough in the bottom of the tank 154. The material which undergoes the centrifuging action is thus dried and is discharged through the discharge mouth 163 of the basket 165 and through the funnel or chute 159 onto the conveyor 160.

The upper end of the centrifuging shaft 162 is adapted to be driven by a motor 167 supported on the framework 161. The motor 167 is connected by means of wires 168 and 169 with a suitable source of electrical energy or to the main power line of the system. Connected in the wire 169 is a motor control switch 170. For the purpose of slowing down or braking the operation of the centrifuge motor 167 a solenoid operated brake unit 171 is secured to one side of the motor casing. Connected to the terminals of the solenoid of the brake unit 171 is a circuit wire 172 and a circuit wire 173. The solenoid circuit wire 172 is connected to a terminal 2 of a centrifuge control electric time switch unit 174 which is mounted on the control board 23 and is identical to the time switch unit 22.

Referring now to the timed automatic control 25 of the consecutive cycles of operation and treatment of material batches which are gravity fed through the machine to be reclaimed and reconditioned, the control circuit comprises main power lines 175 and 176 for the supply of alternating 30 current. Connected in the main power line is a main double throw starting switch 177 for controlling the starting and stopping of the control circuit.

Included in the complete electric circuit for 35 the system are nine standard types of time switches namely, a total cycle time switch 178, the feed control time switch 22 for controlling the feeding of material from the supply and measuring the material in batches, the water 40 control time switch 80 for governing the time and amount of water to be admitted into the wet scrubber unit, the dry scrubber discharge door control time switch 61, the wet scrubber control time switch 93, the desilter control time switch 45 111, the elutriator control time switch 151, the centrifuge control time switch 174 and a cycle reset time switch 179.

All of the nine time switches are of the same 50 standard type and each is provided with a dial lock nut or knob 25 which is adapted to be loosened for setting the dials. Each time switch includes an outer minute time set dial 24 and an inner second time switch dial 26. With the lock knob loosened the minute dial 24 is set for the 55 required time setting in minutes, after which the second dial is set for the required time setting in seconds. The outer dial 24 moves one division for each revolution of the inner dial 26. The time setting is the sum of the readings of the 60 outer and inner dials. After setting the dials, the lock knob 25 is tightened to insure operation of the timer.

Each of the nine time switches is provided with 65 seven terminals, designated L¹, AL², 1, 2, B and M. In each time switch the terminals L¹ and A are connected by a clutch coil C, and the terminals L¹ and B are connected by a synchronous motor S. The terminals B and M of each time switch are connected by a connector bar or wire 70 to connect two switch arms D and E. Connected to each terminal L² is a contact finger T with which switch arm D is positioned to coat. Connected to the terminal 1 is a contact finger 1, and a contact finger 2 is connected to the terminal 2. 75 The two switch contact fingers 1 and 2 are posi-

tioned on opposite sides of a switch arm E to be contacted thereby at timed intervals depending upon the setting of the time switch. In the total cycle time switch 178 and in the reset time switch 179 the terminal 2 and the contact finger 2 are not used.

In the complete circuit arrangement illustrated in Figure 2, the terminal 180 of the main control switch 177 has a circuit wire 181 connected thereto and said wire is connected at its other end to the contact L¹ of the total cycle time switch 178. The terminal L¹ of the reset time switch 179 is connected by means of a circuit wire 182 through the line wire 181. The terminal A of the reset time switch 179 is connected by means of a circuit wire 183 to the terminal 1 of the total cycle time switch. The terminal L² of the reset time switch is connected by a circuit wire 184 to a line wire 185 one end of which is connected to the terminal 186 of the main switch 177. The other end of the line wire 185 is connected to the terminal L² of the total cycle time switch 178. The terminal 1 of the reset time switch 179 has connected thereto one end of a circuit wire 187 the other end of which is connected to the terminal A of the total cycle time switch 178. The terminal 2 of the reset time switch 179 remains dead.

In all the time switches, except the reset time switch 179, the switch contacts T, 1 and 2 are normally open. The reset time switch 179 normally has the switch contacts T and 2 open, while the switch contact 1 is normally closed.

The circuit wire 172 from the centrifuge brake unit 171 is connected to the terminal 2 of the centrifuge time switch unit 174. The circuit wire 173 from the centrifuge brake unit 171 is connected to the centrifuge time switch terminal L¹ and also to the line wire 181. The terminal A of the centrifuge time switch 174 is connected by means of a wire 188 to the circuit wire 187 and the terminal L² of the time switch 174 is connected by a wire 189 to the line wire 185. Connected to the terminal 1 of the time switch 174 is a circuit wire 190 which leads to terminal A of time switch 151.

The elutriator wire 150 leading from the valve unit 147 is connected to the terminal 2 of the elutriator time switch 151 while the line wire 149 from the valve unit 147 connects to the terminal L¹ of the time switch 151 and also to the line wire 181. The terminal L² of the time switch 151 is connected by means of a wire 191 to the line wire 185. Connected to the terminal 1 of the time switch 151 is a wire 192 which is connected to the terminal A of the time switch 111.

The wire 109 from the desiliter valve unit 107 connects up to the terminal 2 of the time switch 111 while the wire 110 from the desiliter valve unit 107 connects up to the terminal L¹ of the desiliter time switch 111 and to the line wire 181. A wire 193 connects the terminal L² of the desiliter time switch 111 with the line wire 185. A wire 194 connects the terminal 1 of the desiliter time switch 111 to the terminal A of the wet scrubber time switch 93.

The wire 91 leading from the wet scrubber valve unit 89 is connected to the terminal 2 of the time switch 93 while the wire 92 from the valve unit 89 is connected to the terminal L¹ of the time switch 93 and also to the line wire 181. A wire 195 is connected to the terminal L² of the time switch 93 and to the line wire 185. A wire 196 connects the terminal 1 of the line

switch 93 with the terminal A of the dry scrubber time switch 61.

The wire 59 from the dry scrubber valve unit 57 connects to the terminal 2 of the time switch 61 while the wire 60 from the valve unit 70 connects to the terminal L¹ of the time switch 61 and also to the line wire 181. A wire 197 connects the terminal L² of the time switch 61 to the line wire 185. A wire 198 connects the terminal 1 of the time switch 61 to the terminal A of the water control time switch 80 and also to the terminal A of the feeder batch control time switch 22.

The wire 78 from the water control valve unit 73 connects to the terminal 2 of the time switch 80 while the wire 79 from the valve unit 73 connects to the terminal L¹ of the time switch 80 and also to the line wire 181. A wire 199 connects the terminal L² of the time switch 80 to the line wire 185. The terminal 1 of the time switch 80 remains dead.

The wire 20 from the batch control valve unit 16 connects to the terminal 2 of the time switch 22 while the wire 21 from the valve unit 16 connects to the terminal L¹ of the time switch 22 and also to the line wire 181. A wire 200 from the terminal L² of the time switch 22 is connected to the line wire 185. The terminal 1 of the time switch 22 remains dead.

By means of the control board 23 and the group of nine time switches mounted thereon and connected with the various material treating mechanisms forming part of the sand reconditioning system, a selective timing arrangement is provided whereby the machine may be operated automatically for production control in the reclaiming or reconditioning of foundry sand and other similar materials.

The circuit arrangement is such that when the centrifuge unit completes the drying of a cleaned batch of material and the elutriator valve 129 is closed the centrifuge time switch 174 having been set for a predetermined time period of operation acts to brake the operation of the centrifuging mechanism to slow the same down thereby permitting discharge and emptying of the centrifuge unit. When the brake is applied the motor control switch 170 is opened to prevent overloading of the motor. After the centrifuge unit is emptied the elutriator time switch 151 opens the control or discharge valve 129 permitting a batch of treated material from the elutriator to be discharged into the centrifuge unit while the desilting unit by the action of its time switch remains closed until the centrifuge unit has been emptied and is ready to receive the next charge. In a similar manner the desiliter unit is next opened to discharge its contents while the wet scrubber unit remains closed until the desiliter is empty and ready to receive a charge. The wet scrubber unit after discharging its contents is closed and the dry scrubber unit is then opened to deposit a measured charge into the wet scrubber unit, in which the delivered charge is first dry treated and then has water mixed therewith. When the dry scrubber unit is emptied and closed by its time control switch the batch mechanisms will deliver a measured charge or batch of material when the doors of the measuring hopper 28 are opened and the doors of the supply hopper 4 are closed. The time switch for the measuring hopper and the supply bin is such that when one opens the other closes.

The time switch circuit arrangement is such that the sequence of operations electrically is up-

wardly from the last or centrifuging treatment, so that a batch of material which has been treated is always discharged from a unit before a new batch of material is admitted. The mechanical sequence of operations of course starts from the uppermost unit, where the material to be reconditioned is delivered and batch measured and is then fed downwardly by gravity in timed controlled steps from one treating unit into another until the cycle is completed. The cycle is controlled by the total time switch 178 which is set to cover a total period which may be greater or equal to the sum of the timing operations of the seven step treatment time switches, so that when a cycle of operations has been completed the reset time switch 179 will act to automatically cause resetting of the total time switch and the various other time switches so that the next cycle of operations may take place.

It will be noted that in this improved reconditioning system the machine is adapted to treat a plurality of batches in continuously repeated sequences, so that there is a batch of reconditioned material discharged from the machine onto the receiving conveyor 160 at the end of every period for which the various treatment time switches have been set. The treatment time switches are all set for the same length of time, so that there is an inter-related timed opening and closing for the adjacently positioned units without any danger of the intermixing of batches during the reconditioning cycle.

During the operation of the machine the water from the main supply pipe 82 is used to deliver water in the wet scrubber and to supply water under pressure to the desilting and the elutriating units. The water which has been used in the elutriating unit and in the centrifuging unit is comparatively clean and is discharged back into the reservoir 124. When the reservoir is filled sufficiently, the main water supply may be shut off or cut down so that the water from the reservoir may be reused by pumping the same into the water pipes supplying the various units of the system.

The improved reclaiming system has the various treatment element steps arranged at different elevations to provide an arrangement whereby the material may be delivered and batch measured and then fed through a continuous downwardly directed course by the action of gravity thereby eliminating the need of providing pumps, conveyors and the like between the different units of the system. The substantially vertical arrangement of the various units has the further advantage of materially saving floor space thereby reducing cost. By providing for the reuse of water in the system, a further reduction in operating cost is accomplished.

The automatic timing arrangement for the system is such that the various units may be properly timed to assure proper opening and closing of the same in relating to the adjacent units so that there will absolutely be no doubling up of the batches as the plurality of successive batches are advanced continuously through the cycles of operation.

It will, of course, be understood that various details of construction and steps in the method may be varied without departing from the principles of this invention, and it is, therefore, not the purpose to limit the patent granted hereon otherwise than necessitated by the scope of the appended claims.

We claim as our invention:

1. The method or process of reclaiming foundry sand and the like for re-use, said method including subjecting a series of batches of material in continuous sequences, each batch to a different treatment as the series of batches are advanced downwardly through a gravity line as each batch of material is consecutively batch measured and intermittently advanced at predetermined intervals of time, subjecting an advanced measured batch of material to dry scrubbing and removing the fines by air suction, partially wetting the dry cleaned batch and subjecting the same to a scouring and mulling treatment to form a paste, treating the paste to a desilting operation and hydraulically removing organic and foreign matter from the resultant batch, subjecting the remainder of the batch to an elutriating action to grade the material and to wet scrub the same and hydraulically remove fines therefrom, and finally subjecting the resultant clean graded batch of material to a centrifugal dehydrating treatment to throw off the water and dry the reclaimed clean batch of material for re-use.

2. The combination dry and wet method of reclaiming used inert foundry sand or the like for re-use comprising advancing the material through a continuously descending line of travel by the action of gravity through a continuous sequence of timed operations comprising batch measuring the material and intermittently advancing the measured batch, subjecting the batch to dry scrubbing and suctioning fines therefrom, then wet scouring and mulling the batch leaving a paste-like batch, subjecting the paste-like batch to a desilting treatment and removing organic and foreign matter therefrom, then subjecting the resultant batch to elutriating actions to wet scrub and grade the material and further separating any remaining fines therefrom leaving a clean graded material, and finally centrifuging the resulting clean graded material to dehydrate and dry the material and then discharge the same.

3. A foundry sand reclamation method consisting of simultaneously advancing batches of material in timed sequences through a continuously descending gravity feed line, each sequence of operations including batch measuring the material and subjecting the batch to dry scrubbing and suctioning to remove fines therefrom, subjecting the batch to wet scouring and mulling treatments to produce a paste-like batch, applying desilting actions to the paste-like batch to remove organic and foreign matter therefrom, then subjecting the resultant batch to elutriating treatments to separate fine graded particles from heavier graded particles and then centrifuging the heavier graded particles to dehydrate and dry the same to produce thoroughly cleaned and substantially dry reclaimed graded sand ready for re-use.

4. The method of reclaiming foundry sand from used inert foundry shakeout material, said method including advancing the material through a continuously descending gravity feed line through a series of independently and collectively timed treatments consisting of dry cleaning and simultaneously removing fines from the material, subjecting said resultant material to wet scouring and mulling treatments to produce a paste-like substance, then desilting the paste-like substance to remove organic and foreign matter leaving a cleaned mixture of different sized sand grains, elutriating the mixture to carry off the fine sand grains and leaving the

17

heavier graded sand grains, and finally dehydrating the heavier graded sand grains by a centrifuging treatment to dry the reclaimed graded sand for re-use.

5. The method of reclaiming foundry sand from used inert foundry shakeout material, said method including feeding the material intermittently through a continuously descending gravity feed line through a series of automatically timed operating and rest steps consisting of measuring and dry cleaning the material and suctioning off the resultant fines, wetting the material and simultaneously scouring and mulling the same to form a paste-like substance, grading the paste-like substance by subjecting the same consecutively to desilting and elutriating actions, and finally subjecting the cleaned graded material to a centrifuging treatment to dry the same ready for re-use.

6. The method of reclaiming inert granular materials for re-use consisting of gravity feeding the material in separated measured batches through consecutive sequences of independently timed steps each having timed operating and rest intervals for controlling the advance of the batches independently through separately consummated dry cleaning treatments involving air removal of resultant fines, and separately consummated wet cleaning treatments for scouring, scrubbing and then grading the clean sand, and finally dehydrating the resultant graded sand to dry the same ready for re-use.

7. The continuous batch processing of previously used material to reclaim graded cleaned quantities thereof by independently conducting measured batches of the material through a continuously descending gravity feed line through inter-timed separately consummated steps each including timed operating and rest intervals, said steps consisting of dry cleaning and scrubbing the material and suctioning fines therefrom, then wet treating and cleaning the material and hydraulically grading out the re-usable cleaned quantities of the material, and finally subjecting the cleaned graded material to dehydrating treatments to dry the same ready for re-use.

8. A foundry sand reclaiming system comprising in combination a supply hopper for carrying crushed demetalized inert foundry sand for reclamation, means therebelow for measuring the sand into batches, means for independently dry scrubbing and air suctioning the batches, means for wetting, scouring and mulling the sand batches to form a sand paste of each batch, means for receiving the paste including means for desilting the paste by removing organic and foreign matter therefrom leaving cleaned sand, means for elutriating the cleaned sand to grade the same, means for centrifugally drying the graded sand for re-use, all of said means being connected one below the other in the order mentioned in a continuously descending series to

18

form a continuous gravity feed line for the system, and timers connected to one another and to said various means to automatically control the timed operation of each of said means.

5 9. In a foundry sand reclaiming system, a continuous gravity feed line for reclaiming foundry sand, said line comprising measuring means for batch measuring the sand, dry scrubbing means for receiving the sand batches, suction means for drawing off the fines from the sand while being dry scrubbed, means for wetting, scouring and mulling the sand, desilting means for removing organic and foreign matter from the wet scrubbed sand, means for elutriating the wet cleaned sand to grade the sand, settling means for receiving water and fines from the elutriating means, centrifuging means for dehydrating and drying the clean graded sand and discharging the resultant water into the settling means, means operable to draw off the water from the settling means to re-use the water in the operation of the desilting means to reduce water consumption, and timing means connected with and automatically governing the operation of the sand treating means in timed sequence depending upon the timing of the longest step in the sequence.
